US00D806358S

(12) United States Design Patent (10) Patent No.: US D806,358 S
(45) Date of Patent:  Jan. 2, 2018

(54) SWIMSUIT

(71) Applicant: Speedo International Limited, London (GB)

(72) Inventors: Karen Flockton, London (GB); Ben Hardman, London (GB); Tim Sharpe, London (GB); Chris Johnson, London (GB); Dawn Nixon, London (GB); Joseph Santry, London (GB)

(73) Assignee: Speedo International Limited, London (GB)

() Term: 15 Years

(21) Appl. No.: 29/555,007

(22) Filed: Feb. 17, 2016

(30) Foreign Application Priority Data

(74) Attorney, Agent, or Firm — Fross Zelnick Lehrman & Zissu P.C.; Charles T. J. Weigell, Esq.

(57) CLAIM

The ornamental design for a swimsuit, as shown and described.

DESCRIPTION

FIG. 1 is a front right perspective view of a swimsuit design; FIG. 2 is a front left perspective view thereof;

FIG. 3 is a rear right perspective view thereof, with racerback; and,

FIG. 4 is a rear left perspective view thereof, with racerback. The broken line shown in the drawings are included for the purpose of illustrating environmental structure and form no part of claimed design.

1 Claim, 4 Drawing Sheets
